UNITED STATES PATENT OFFICE.

JOHN B. WEBER, OF UNION HILL, NEW JERSEY, ASSIGNOR TO THE OSBORNE COMPANY, OF NEWARK, NEW JERSEY, A CORPORATION OF NEW JERSEY.

CALENDAR-HEAD.

1,347,882.

Specification of Letters Patent.

Patented July 27, 1920.

Application filed March 3, 1920. Serial No. 363,030.

To all whom it may concern:

Be it known that I, JOHN B. WEBER, a citizen of the United States, residing at Union Hill, in the county of Hudson and 5 State of New Jersey, have invented certain new and useful Improvements in Calendar-Heads, of which the following is a specification.

My invention relates to the heads or upper rims of wall calendars by means of which the sheet or sheets composing the calendar are secured together or held in place and to which the means for suspending the calendar are usually attached.

10 Such heads have heretofore been made of a strip of tin folded over with the sheet or sheets of the calendar.

These tin heads are easily bent and moreover by reason of their crude appearance 20 are not adapted for use with the better class of ornamental calendars, known as "calendars de luxe," which usually consist of a back of heavy paper to which a picture is adhesively secured and a mat surrounding the picture, the mat and back being held together by a ribbon by means of which the calendar is suspended.

The object of my improvements is to provide a more economical construction of such 30 calendars de luxe while preserving their ornamental appearance and also to provide a more sightly and durable and efficient calendar head. To this end I provide the strip of tin such as calendar heads have heretofore been made of with a covering of paper, which is in the first instance folded so as to 35 cover the strip, which thus forms the core of the calendar head, and is then bent or crimped with the core to form the head.

40 The paper covering of the core may be of any color and quality, thus harmonizing with the color and quality of the paper used in the calendar. Besides this the calendar head has greater rigidity than when 45 composed simply of a bent or folded piece of tin and the calendar sheets are more firmly held by reason of the greater friction of the paper surface.

In applying such a head in the formation 50 of a calendar de luxe, instead of adhesively securing a picture to the calendar back and then binding this to a mat with ribbon, the back, picture and mat are

loosely assembled and then inserted and held in the calendar head in the usual 55 manner, the paper covering of the head being made to harmonize with the other parts of the calendar.

The invention will be best understood by reference to the accompanying drawings 60 Figure 1 of which shows a calendar head in the first stage of construction with the paper covering folded around the metal core; Fig. 2 shows the calendar head folded or bent over ready to receive the sheet 65 or sheets forming the calendar; Fig. 3 shows the calendar head in its completed form with the parts forming a calendar de luxe held therein, Fig. 4 shows a calendar head with its paper covering extended to form 70 a calendar back, and Fig. 5 is a sectional view showing a modified form of construction.

Referring to the drawings A, indicates a strip of thin pliable metal, as tin, which 75 constitutes the core of the calendar head around which is wrapped, or folded a strip of paper, B, forming a covering therefor.

In forming the calendar head the core, A, with the covering, B, is first folded or bent 80 over along one edge so as to form a lip, C, as shown in Fig. 2. One edge of the sheet or sheets forming the calendar, as D, E, Fig. 4, is then inserted under the lip, C, and this is again folded so as to assume 85 the shape shown in Figs. 3 and 4. Thus the calendar sheets are folded in with the head and held firmly therein.

In applying the invention to a calendar de luxe, comprising, a back, F, a picture, G, 90 and a mat, H, surrounding the picture, the picture is not adhesively secured to the back, as has heretofore been the case, but is assembled loosely therewith together with the mat, and the three are then secured in 95 the calendar head in the same manner as other calendar sheets, as shown in Fig. 3. Thus a more economical form of construction is provided and at the same time the warping to which such calendars have been 100 subject heretofore is avoided. This use of a calendar head with such calendars is made possible by the paper covering of the head which can be made to harmonize in color and texture with the visible parts of the calendar and at the same time the relatively 105

thick and heavy back and mat are thereby enabled to be firmly held in the calendar head.

In the form of construction shown in Fig. 4, the free edge, *b*, of the covering, *B*, of the calendar head is extended so as to form a back for the calendar.

Instead of folding the calendar head with a double fold as shown in Figs. 1-4 I may fold the head only once as shown in Fig. 5.

The holding of the calendar sheets in the head with such a single fold is made possible, when the head is pressed securely down upon the sheets, by the friction of the paper covering, *B*, which grips the sheets. In order, however, to insure the retention of the calendar sheets in the head I may indent the metal of the head from the back so as to press upon the sheets as shown at *A'*.

This construction has the advantage of providing a thinner head, which presents an improved appearance and occupies less space when the calenders are packed in quantity for shipment, than where a double fold in the head is employed.

Besides the greatly improved appearance imparted to a calendar by the use of my invention it also presents the advantages of increased stiffness in the head thus enabling the use of a lighter strip of metal and the

necessity of coloring the metal is done away with, also the calendar sheets are held more firmly by the paper surface than heretofore.

Having thus described my invention what I claim as new and desire to secure by Letters Patent is:—

1. A calendar head comprising a core of metal and a covering of paper surrounding the core and folded over with the core to form the calendar head. 40

2. A calendar head comprising a core of flexible metal, and a covering of paper surrounding the core, the core and covering being folded over together to hold the calendar sheets. 45

3. A calendar consisting of a back, a picture and a mat surrounding the picture, the same being loosely assembled and held in a head consisting of a metal core and a covering of paper surrounding the core and folded over with the core to form the calendar head. 50

4. A calendar head consisting of a strip of metal provided with a covering of paper and bent over so as to form a groove to receive the calendar and having the metal indented to engage the calendar. 55

In testimony whereof I have affixed my signature this first day of March, 1920.

JOHN B. WEBER.
